UNITED STATES PATENT OFFICE

CHARLES R. BAKER, OF EVANSTON, ILLINOIS

BURNER

Application filed March 18, 1929. Serial No. 347,869.

This invention relates to an improved combination Bunsen burner and blow-pipe of compact and simplified form wherein an illuminating gas supply pipe and a compressed air pipe are connected to a common base having a Bunsen burner standard mounted thereon and provided with a plurality of control valves for the operation of the Bunsen burner portion of the device, and furthermore provided with a needle valve mechanism controlling the supply of compressed air to a compressed air pipe which projects axially upward through the Bunsen burner standard and through a Bunsen burner nozzle removably engaged on the standard.

It is an object of this invention to provide an improved combination Bunsen burner having a blow pipe arrangement adapted to be operated by compressed air controlled by a needle valve arrangement whereby a current of compressed air is adapted to be delivered through a gas flame to produce a flame pencil of great heat intensity to permit a substance on which the flame pencil is directed to be intensely heated, fused or vitrified.

It is a further object of this invention to provide an improved burner which may be used either as a Bunsen burner or as a blow-pipe burner with the blow-pipe burner being provided with a control valve for governing the passage of compressed air axially into a gas flame to produce a required flame pencil.

It is an important object of this invention to provide a combination Bunsen burner and blow pipe device of compact form wherein a needle valve controlled compressed air supply pipe or stem is axially mounted within a Bunsen burner standard and projects upwardly through the removable cap or nozzle of the Bunsen burner so that either a Bunsen flame or a blow pipe pencil flame may be emitted from the removable nozzle of the burner depending upon the adjustment of a plurality of control valves which govern the supply of gas and air to the burner.

Other and further important objects of this invention will be apparent from the dis-

closures in the specification and the accompanying drawings.

The invention (in a preferred form) is illustrated in the drawings as hereinafter more fully described.

On the drawings:

Figure 1 is a top plan view of an improved burner embodying the principles of this invention and having fragmentary portions of a gas supply hose and a compressed air supply hose connected therewith.

Figure 2 is a side elevation of the burner.

Figure 3 is a bottom plan view of the burner illustrating the operations of the Bunsen burner air control valve in dotted line.

Figure 4 is a detailed sectional view taken on line IV—IV of Figure 2 with parts in elevation.

Figure 5 is a fragmentary horizontal section through the base portion of the burner taken on line V—V of Figure 2.

As shown on the drawings:—

The reference numeral 1 indicates a metal base plate provided with an integral radially directed arm or extension 2 having a leg or foot 3 integrally formed at the bottom of the outer end thereof. The arm or extension 2 projects radially inwardly beneath the base plate 1 forming a boss 4 the inner end of which is rounded. The base plate 1 is provided on its underside with two legs or feet 5 which furthermore serve as stop members for limiting the movement of the lever arm or handle 6 which is integrally formed radially on an air control valve or disc 7 which is rotatably mounted on the underside of the boss 4 centrally beneath the base plate 1. The other end of the valve operating handle or lever 6 is bent upwardly and then inwardly over the top of the base plate 1 to afford an indicator or pointer 8 to designate the position of the air control valve 7. The air control valve 7 is provided with a pair of air intake openings or apertures 9 which are positioned diametrically opposite one another on opposite sides of the mounting screw 10 of the valve 7. The valve 7 is the Bunsen air control valve which controls the admittance of atmospheric air from

the bottom of the base plate upwardly into a passaged Bunsen burner standard 11 which is integrally formed centrally upon the top of the base plate 1. The upper end of the 5 standard 11 is of reduced diameter and is externally threaded at 12 to removably receive the internally threaded cap or hood portion 13 of a Bunsen flame nozzle or pipe 14 which is integrally formed axially upon 10 the top of the cap or hood 13. The standard 11 is provided with two passages 15 which extend longitudinally through the standard and continue through the inner portion of 15 the boss 4. When the atmospheric air control valve 7 is in open position the apertures 9 thereof are adapted to register with the passages 15 to permit atmospheric air to pass upwardly through the standard and out of the burner nozzle 14.

19 Rigidly secured on the outer end of the arm or extension 2 is a tapered nipple or stem 16 which is longitudinally passaged and is adapted to have removably engaged thereon one end of a gas supply hose or pipe 17 25 whereby illuminating gas may be supplied to the burner. The gas supply passage in the nipple or stem 16 registers with a gas passage 18 formed in the boss 4 of the base of the burner as clearly illustrated in Figure 5. A gas control valve 19 is rotatably supported in the arm 2 and projects through the passage 18 to control the flow of gas therethrough into a pipe 21 which is embedded longitudinally within a passage provided in 30 the boss 4 as shown in Figure 5. The outer end of the pipe 21 is closed by means of a screw plug 20 or other suitable means. The top of the embedded gas pipe 21 is provided with a pair of gas outlet apertures 37 positioned to permit a supply of gas to be discharged therefrom into the passages 15 provided in the burner standard 11.

35 It will thus be noted that by adjusting the gas control valve 19 that a supply of illuminating gas may be admitted into the burner base arm 2 through the passage 18 and into the embedded pipe 21 from which the gas is permitted to escape or pass upwardly through the outlet apertures 37 (Figure 1) into the passages 15 of the burner standard 11 to carburate or mix with a supply of air at atmospheric pressure which is admitted through the bottom of the burner through the valve openings 9 of the disc 40 valve 7 which is operable by means of the handle or lever 6, so that the valve may be adjusted with the openings 9 thereof in open position as indicated in full lines in Figure 3, or in a closed position as indicated by the 45 dotted lines of said figure.

50 The improved burner is readily adapted to be converted from a Bunsen burner into a blow type burner. Also rigidly secured in the outer end of the extension arm 2 of 55 the burner base is a tapered nipple or stem 60

22 provided with a longitudinal air intake passage 23, the inner end of which communicates with a horizontal passage 24 provided in the boss 4 of the base member. The inner end of the compressed air passage 24 communicates with the lower end of a vertical auxiliary compressed air passage 25 which is formed in the standard 11 as clearly illustrated in Fig. 4. The upper end of the vertical air passage 25 is closed by means of a screw plug 26 or other suitable means. Removably engaged on the compressed air intake nipple or stem 22 is one end of a compressed air supply hose or tube 27, the other end of which may be connected with any suitable source of compressed air.

55 Integrally formed radially on one side of the standard 11 is a sleeve or pipe 28 which is externally threaded to removably receive an internally threaded and apertured cap 29. The cap 29 holds a packing ring 30 (Fig. 4) against the end of the sleeve 28 around a threaded needle valve stem 31 which is adjustably threaded through the sleeve 28 and 60 is provided on its exterior end with a disc head 32 to facilitate adjustment of the tapered inner valve end of the valve stem 31. The standard 11 is provided with a radial passage 33 which connects up with the passage in the sleeve 28 and crosses the vertical compressed air passage 25 to permit compressed air from the passage 25 to enter the radial passage 33 when the needle valve is open. The inner end of the radial air passage 33 communicates with an opening 34 provided in a compressed air tube or pipe 35 which is axially engaged in an axial passage provided in the standard 11. The compressed air pipe or nozzle 35 projects upwardly above the top end of the standard 11 and has the upper end thereof tapered to form a tip 36. The compressed air tube or pipe 35 projects axially through the cap or hood 13 and through the greater portion 65 of the burner nozzle 14 with the compressed air tip 36 positioned a short distance below the outer opened end of said nozzle 14, as clearly illustrated in Figure 4.

70 The operation of the improved combined Bunsen and blow-pipe burner is very simple. When it is desired to use the improved burner as a Bunsen burner only the needle valve 31 is closed thereby shutting off the supply of compressed air from the compressed air supply pipe 27 so that no compressed air is permitted to enter the axially disposed air tube or nozzle 35-36. When the handle or lever 6 of the Bunsen burner air control valve 7 is in the full line position of Figure 3 against the stop or foot 5 the pointer or indicator 8 is in register with the arrow "B" and the valve 7 and the lower ends of the air intake passages 15 are open. When the air valve 7 is moved into a closed 75

position the gas control valve 19 may also be closed. If only a gas flame is desired the gas valve 19 may be opened and the air valve 7 is then left closed.

5 To use the Bunsen burner the atmospheric air control valve 7 is opened by moving the valve control arm 6 from its closed position "A" in Figure 1 into a completely open position indicated by "B" in Figure 1. The 10 atmospheric air control valve 7 may of course be opened any desired amount, so that any desired amount of air at atmospheric pressure may be admitted into the bottom of the burner standard 11. The gas 15 valve 19 may now be opened any desired amount to permit the gas from the supply hose 17 to be admitted through the nipple 16 and the gas passage 18, from which passage the gas is permitted to flow and pass 20 through the gas tube or pipe 21 from which the gas is permitted to escape through the outlet aperture or opening 37 provided in the top of the tube or pipe 17 directly in the path of the passages 15 through which air 25 is admitted. The gases admitted into the burner standard pass upwardly through the burner nozzle 14 and are carburated with atmospheric air which is drawn upwardly through the bottom of the burner through 30 the air passages 15. The nozzle or jet 14 of the burner permits the gas and air mixtures to escape through the upper end thereof so that the burner may be lighted by means of a match to produce a feebly luminous but extremely hot flame. The 35 amount of oxygen supplied through the illuminating gas coming from the supply pipe may be varied by adjusting the atmospheric air control valve 7.

40 When it is desired to use the improved burner as a blow flame burner device it is only necessary to open the compressed air control needle valve 31 by turning the disc head 32 so that compressed air from the compressed air supply pipe 27 may be admitted through the passages 23 and 24 into the vertical passage 25 from which the compressed air is permitted to pass through the radial passage 33 into the compressed air nozzle or pipe 35 through the opening 34. The compressed air is thus permitted to be discharged through the restricted outlet tip 36 directly and axially into the gas flame at the upper end of the nozzle 14. The blast 45 or current of compressed air driven through the gas flame produces a pencil flame of great heat intensity which may be directed at will upon a suitable object or objects to fuse, vitrify or heat the same intensely. 50 When the device is used as a blow flame mechanism, the atmospheric air control valve 7 is closed, so that only an ordinary gas flame issues from the burner nozzle 14. The blow flame is produced by opening the 55 compressed air control valve 31 permitting

compressed air to be admitted directly into the gas flame to produce a pencil blow flame.

It will of course be understood that many changes may be made and many details of construction may be varied through a wide range without departing from the principles of this invention, and it is therefore not purposed limiting the patent granted hereon otherwise than necessitated by the scope of the appended claims. 75

I claim as my invention:

1. A burner comprising a passaged base, a standard mounted thereon, an air control valve mounted on said passaged base to control the supply of air to said standard, a 80 gas control valve mechanism in said passaged base for controlling the supply of gas into said standard to mix with the atmospheric air to permit the burner when lighted to produce a Bunsen flame, a compressed air supply nozzle mounted in said standard, and a needle valve mechanism for controlling the supply of compressed air to said compressed air supply nozzle to be directed axially into the gas flame to convert the same into a 85 blow-pipe flame when the air control valve is closed. 90

2. A burner comprising a passaged base, a passaged standard mounted thereon, a nozzle removably engaged on said standard, an atmospheric air control valve mounted on said base, a gas control valve mounted on said base for controlling the supply of gas through said standard, a compressed air jet in said standard and projecting through 100 a portion of said nozzle, and a compressed air supply valve on said standard for controlling the flow of compressed air through said compressed air jet. 105

3. A burner comprising a passaged apertured base, a passaged standard mounted thereon, a burner nozzle removably mounted on said standard, a primary air control valve mounted on said apertured base to control the supply of atmospheric air through said 110 burner nozzle, a gas control valve mounted on said base for controlling the supply of gas to said nozzle, and means disposed within said nozzle to permit a supply of compressed air to be admitted into said nozzle. 115

4. A burner comprising a passaged base, a nozzle removably mounted thereon, an atmospheric air supply control valve adjustably mounted on said base, a gas supply control valve mounted on said base, a compressed air jet axially mounted in said nozzle, and control means connected therewith for controlling the supply of compressed air through said nozzle to convert a gas flame into a blow flame. 120 125

5. A burner of the class described comprising a base having passages therein, a standard mounted on said base and also provided with passages, a burner nozzle removably mounted on said standard, an atmos- 130

pheric control valve mounted on said base, a gas control valve mounted on said base, a compressed air supply jet mounted in said standard and projecting part way through said nozzle, and a compressed air control valve mounted on said standard for controlling the passage of compressed air from said jet through said nozzle.

6. A burner of the class described comprising a passaged base, a passaged standard integrally formed thereon, an atmospheric control valve mounted on said base, a handle connected therewith for operating the same, legs formed on said base to support the same and to serve as stops for the movement of the atmospheric air control valve handle, a gas control valve mounted on said base to govern the supply of gas through said standard, a nozzle removably mounted on said standard and adapted to permit a supply of atmospheric air and gas to be ejected from the mouth thereof and lighted to produce a Bunsen flame, a compressed air supply jet axially mounted in said standard and projecting into said nozzle to direct a blast of compressed air axially through a gas flame to convert the same into a blow flame, and a compressed air control valve on said standard and connected with said jet to control the passage of compressed air therethrough.

7. A burner of the class described comprising a passaged base, a nozzle removably mounted thereon, a gas control valve mounted on said base to control the supply of gas through said nozzle, an atmospheric air control valve on said base to control the supply of atmospheric air through said nozzle to be carburated with the gas, a compressed air jet mounted in said base and projecting into said nozzle, and means mounted on the base for controlling the passage of compressed air through said jet and through said nozzle to be driven through the gas flame resulting from the burning of gas emitted from said nozzle to convert said gas flame into a pencil blow flame.

In testimony whereof I have hereunto subscribed my name at Chicago, Cook County, Illinois.
